UNITED STATES PATENT OFFICE.

SALEM T. LAMB, OF NEW ALBANY, INDIANA, ASSIGNOR OF THREE-FOURTHS
TO ARLANDO T. HARRELL AND HARRY C. PARKER, BOTH OF SAME PLACE.

BURGLAR-ALARM.

SPECIFICATION forming part of Letters Patent No. 368,095, dated August 9, 1887.

Application filed February 23, 1887. Serial No. 222,638. (No model.)

To all whom it may concern:

Be it known that I, SALEM T. LAMB, a citizen of the United States, and a resident of New Albany, Floyd county, State of Indiana, have 5 invented certain new and useful Improvements in Burglar-Alarms, of which the following is a specification.

This invention relates to that class of burglar-alarms in which an audible alarm is produced 10 by the contact of parts or the ignition of an explosive matter; and it consists in the peculiar construction and arrangement of the various parts of the alarm, as hereinafter fully set forth, and pointed out in the claims.

15 In the drawings, Figure 1 is a perspective view showing the device applied to a window in such a manner as to be operated by raising the sash; Fig. 2, a view showing the device applied to a door, so as to be operated on opening the said door. Figs. 3 and 4 are rear views 20 of the device, illustrating the operation thereof. Fig. 5 is a perspective view of a detail, and Fig. 6 an end view of the device in a closed position. Fig. 7 is a view illustrating the use 25 of a movable contact on a door; Fig. 8, a modification.

A and B are two plates or parts, which are hinged together by a pintle, C, extending through ears 2 and 3 on the plate A and ears 30 4 and 5 on the plate B, and secured to one or both ears of one of the plates, the ears projecting from the edges of the plates A and B, near the ends thereof, at right angles to the said edges and to the faces of the plates.

35 The plate A is provided with holes for the passage of screws, whereby it may be secured to a window-easing or door-frame, and preferably carries a projecting stud, a, constituting a hammer, sharpened and fastened securely 40 to or formed as part of the plate, and the plate B is provided with an arm, 6, projecting laterally from the edge opposite that hinged to the plate A, and carrying a socketed projection, 7, adapted to receive a cap or cartridge.

45 The stud a and the projection 7 are so placed that they will come in contact when the plates are brought to the position shown in Fig. 6.

A coiled spring, D, surrounds the pintle or bolt C and bears against the ears 2 and 5, and 50 has one end secured to the plate A and the

other end to the plate B in such a manner that the tendency of the spring is to retain the plates in their closed position, (shown in Fig. 6,) or to forcibly return the plate B to such position after it has been moved to the position 55 shown in dotted lines in the said figure. The ends of the spring are preferably secured as shown, being seated in short grooves 8 in the back of the plates and passing through holes or passages 9 in said plates at the termination 60 of the said grooves.

On the contiguous faces of the ears 2 and 4 of the plates A and B are spiral inclines 15 16, the said inclines terminating in shoulders 10 17, as shown in Figs. 3, 4, and 5, and the spring 65 D tends to force the said ears and inclines toward each other.

The faces of the shoulders are slightly beveled or inclined, so that if sufficient force be applied to swing the plate B the said shoulders will move one over the other and the plate will slide on the pintle in the direction of the arrow, Fig. 4, until the shoulders are out of contact, when the spring will quickly and forcibly move the plate B into contact with the 75 plate A, effecting a forcible contact of the projections a 7, producing a sharp rap, or exploding a cap, if one has been placed in the socket, thus giving an alarm.

Both the spiral and the longitudinal action 80 of the spring are utilized, the longitudinal action tending to force the ears 2 4 together and preventing the shoulders from slipping over each other, and the spiral action closing the plate B toward the plate A as soon as the shoulders 85 have escaped contact. As the shoulders are slightly beveled, any excessive pressure tending to swing the plate B will cause one shoulder to ride over the other, and thus release the plate B.

90 The window-sash is provided with a pin, 12, so arranged that when the plate B is locked in its open position and the sash is raised but a short distance the pin will engage with the rear side of the arm 6 and will turn said plate B on its pintle until the shoulders escape contact, when the spring will carry the plates together in the manner before set forth.

95 The frame of the alarm projects out, so that a curtain, if used on the window, will be held 100

away from the cap or cartridge, and will thus be protected when the explosion takes place. In Fig. 2 the device is shown applied to a door-frame and the door provided with a contact piece or plate, 13, to protect the edge, which will come in contact when opened with the arm 6 of the plate B. In some cases said contact-piece may be movable, so as to be turned into position to strike the movable plate of the alarm, and the contact-piece may be locked in place to insure contact. This arrangement is desirable for the outer door of a house, so that after fastening the windows and other doors from the inside a party can set the alarm, close the outer door, and then by means of a key or adjusting device turn the contact-piece into position to strike the alarm and lock it in place.

Fig. 7 shows one arrangement where a contact-piece, 13, is hinged in a case at x' , so as to be turned from the position shown in dotted lines to a position (shown in full lines) back of the movable plate of the alarm, the door having a key-hole at the opposite side. Fig. 7 also shows another contact-piece in the form of a bolt, 13, sliding in a lock-case, 21, and moved by a key, as usual, any suitable arrangement of tumblers locking the bolt after it is thrown.

Fig. 8 shows the device applied to the lower sash of a window in such manner that the raising of said sash or the lowering of the upper sash will cause the alarm to operate.

Without limiting myself to the precise construction and arrangement of parts shown, I claim—

1. A burglar alarm consisting of a securing-plate, a spring-actuated plate hinged to the securing-plate and movable laterally and longitudinally, and engaging-shoulders on the plates to frictionally retain them in their open position, one of said plates holding a detonator and the other acting as a hammer to explode the same, substantially as described.

45 2. A burglar-alarm consisting of a securing-plate, a movable plate, ears with inclines and shoulders on said plates, a pintle passing through said ears and loosely securing the plates together, and a spring bearing against 50 the ears and face of the movable plate to carry and move it on its pintle, one of said plates carrying a detonator and the other a hammer or contact-piece, substantially as set forth, for the purpose specified.

3. A burglar-alarm consisting of a securing-plate provided at one side with ears and carrying a projection, a movable spring-actuated plate, likewise provided at one side with ears which alternate with the ears on the securing-plate, a holder for a cap or cartridge carried by said spring-actuated plate, and a pintle passing through said ears and loosely connecting the plates together, the adjacent faces of the ears being inclined and provided with shoulders, substantially as and for the purpose described. 55

4. In a burglar-alarm, the combination of two plates provided on one side with ears alternately arranged, as shown, and respectively carrying a detonator and a hammer, a pintle passing through the ears and loosely connecting the plates, and a coil-spring supported by the pintle and connected at its opposite ends to the plates, the contiguous faces of one pair of ears being oppositely inclined and each provided with a shoulder, substantially as and for the purpose described. 70

5. The combination, in a burglar-alarm, of two plates loosely hinged together, one of the plates acting as a hammer and the other carrying a detonator, an interposed spring connected to the plates and normally tending to forcibly swing them toward each other, means, substantially as described, for locking the plates in their separated position, and a contact-piece carried by a sash or other movable object in line with one of said plates, whereby upon the movement of said contact-piece the plates are released, substantially as and for the purpose described. 85

6. In a burglar-alarm, a plate carried by a sash and provided with a projecting ear to receive securing bolts or screws, in combination with a movable spring-actuated plate loosely hinged to the edge of said first plate, and devices, substantially as described, to retain the plates in open position, one of the plates acting as a hammer and the other supporting a detonator, as set forth. 90

In testimony whereof I have signed my name to this specification in the presence of two subscribing witnesses. 95
